KNURLING DEVICE

Cernyw F. Jones, Economy, Ind., assignor to
 Perfect Circle Corporation, Hagerstown, Ind.,
 a corporation of Indiana

Application June 22, 1949, Serial No. 100,649

1 Claim. (Cl. 80—5.1)

1

This invention relates generally to a knurling device for knurling the peripheral surface of a cylindrical object and more particularly to a device for knurling predetermined areas on the peripheral surface of a hollow cylindrical article such as a piston for an internal combustion engine.

With continued operation of an internal combustion engine, the pistons and cylinders tend to wear or become distorted with the result that the normal fit of the pistons within the cylinders is lost. This condition is often characterized by "piston slap" and other evidence of excessive looseness. The lack of a proper fit between the piston and the cylinder is objectionable since it impairs engine efficiency and has an adverse effect on the economy of operation.

Various means for correcting this condition have been employed, one method involving the expansion of the outer wall or skirt portion of the piston sufficiently to reestablish the normal fit between piston and cylinder. Such expansion may be accomplished, for example, by knurling the outer surface of the piston to form roughened areas on the thrust faces thereof having an interrupted surface comprising projecting portions with intervening depressions. During knurling the metal is extruded or swaged to a sufficient extent so that the projections formed on the piston surface extend outwardly to the desired increased size whereby the proper fit between the piston and the cylinder is realized.

A machine or tool for knurling the outer surface of a hollow piston should preferably be provided with an anvil member or other supporting means adapted to engage and support the piston internally while a knurling element engages the exterior of the piston under pressure. However, the interior surface of the skirt portion of a piston is usually quite uneven in the area between the wrist pin bosses, because of various protuberances and surface irregularities such as reinforcing ribs, partial machining of the interior surface, and general surface roughness characteristic of cast articles. Thus, a satisfactory knurling device must be provided with means for accommodating the variations in piston wall thickness while at the same time permitting a substantially constant knurling pressure to be maintained against the outer surface of the piston.

Accordingly, one object of my invention is to provide a device for knurling the exterior surfaces of pistons which readily accommodates variations in piston wall thickness while permitting the application of a substantially constant knurling pressure.

2

Another object of my invention is to provide a device for knurling the exterior surfaces of pistons having a rigid supporting member for engaging the interior of the piston and a movable knurling member for engaging the exterior of the piston, the spacing between said members being variable under manual control by the operator whereby to accommodate protuberances and other irregularities on the interior surface of the piston.

An additional object of the invention is to provide a hand operated device for knurling the exterior surfaces of pistons which is of simple rugged construction and is relatively portable in the sense that it requires no permanent mounting and may, for example, be held in a vise or other bench type support.

A further object of my invention is to provide a simple hand-operated mechanism for knurling the exterior surfaces of pistons in combination with a steady rest to facilitate location of the piston prior to knurling.

Other objects and advantages of the invention will become apparent from the subsequent detailed description of the invention and the accompanying drawings in which:

Fig. 1 is a plan view of a knurling device comprising one specific embodiment of my invention;

Fig. 2 is an end view of the device as viewed from the right in Fig. 1;

Fig. 3 is a front elevational view of the device;

Fig. 4 is an end view of the device with portions thereof in section as taken along the line 4—4 of Fig. 3; and

Fig. 5 is a sectional view taken along the line 5—5 of Fig. 4.

The knurling device comprising the present invention is provided with a pair of cooperating anvil and knurling elements, the anvil element being arranged to support the piston internally while the knurling elements bear against the outer surface of the piston. The knurling element is preferably in the form of a small roller which is applied to the outer surface of the piston in rolling relation therewith so that, by rolling the knurling roller on the surface, the resultant area knurled in one application of the tool comprises a band having a width equal to the width of the roller. Usually the roller is relatively narrow and traverses the piston circumferentially so that a plurality of such knurled bands are required to cover a desired area longitudinally of the piston. The knurled bands may, of course, be disposed in continuous abutting relation to one another or they may be slightly spaced from each other longitudinally of the piston.

55

With a piston for an internal combustion engine, it is necessary to knurl only the thrust faces of the piston skirt, i. e. those portions which are subjected to lateral thrust against the cylinder wall due to the position of the connecting rod. Thus, the knurling operation may be restricted to the portions of the piston skirt lying intermediate the wrist-pin holes on opposite sides of the piston. The knurled area preferably starts immediately below the ring grooves at the upper end of the piston and may extend axially or longitudinally for the full length of the piston skirt. If desired, the knurled band at the extreme outer end of the skirt may be spaced differently from the remaining bands in order to position the outermost band as close as possible to the edge of the piston.

In addition to effecting expansion of the piston metal by extrusion thereof, in the manner hereinbefore described, whereby to reestablish a proper fit between the piston and the cylinder, the knurled surface obtained by my invention also offers other important advantages. For example, it has been found that better performance is obtained in a reciprocating piston and cylinder, or other like construction, if one of the two surfaces is of an interrupted nature comprising projecting portions with intervening depressions, such as may be provided by knurling. A surface of this character has been found to run cooler than an absolutely smooth surface, for pistons as well as other cylindrical objects adapted to reciprocate within a bore. Another advantage inherent in knurling the surfaces of pistons and like articles is found in the improved wearing qualities of the knurled surface resulting from the hardening effects of cold working the metal. In addition, the interrupted surface afforded by knurling provides a series of pockets or reservoirs which serve to retain lubricating oil and thereby maintain a continuous supply of lubricant at the surface-contacting areas.

It will be apparent, therefore, that, in addition to the obvious utility of knurling old or worn pistons in order to expand the same, knurling may also be resorted to in the case of new pistons or original assemblies of pistons within their cylinders in order to attain the other advantages mentioned above. While the knurling devices comprising the present invention are designed primarily for knurling pistons, the invention is not limited in this manner but embraces the knurling of the peripheral surfaces of hollow cylindrical articles generally.

The term "knurling" as used throughout the specification and the claims is not limited to the ordinary form of knurling involving grooves arranged in a criss-cross pattern, but rather is used in a broad sense to include any surface formation involving alternate depressed and raised portions regardless of whether one or the other or both of said portions are continuous throughout the area having such formation. Thus, the term includes not only the criss-cross pattern but also a pattern formed by parallel grooves or by isolated indentations resulting in connected raised portions.

As hereinbefore mentioned, an important object of my invention is to provide a knurling device for pistons which is designed to accommodate varying piston wall thicknesses due to internal protuberances or surface irregularities while at the same time permitting the application of substantially constant knurling pressure. I accomplish this end broadly by providing a

rigidly mounted anvil member and a cooperating knurling member mounted for pivotal movement toward and away from the anvil member in combination with manually operable lever means for controlling the knurling pressure.

Referring now to the drawings, which show by way of illustration one specific embodiment of my invention, the device comprises an elongated body member or base, indicated generally at 11, having a central portion 12 adapted to be received between the clamping jaws of a vise or other suitable clamping means for supporting the device. Projecting upwardly at one end of the base 11 is a pair of longitudinally spaced upright brackets 13 extending rearwardly at their upper portions and overhanging the base 11, as seen most clearly in Fig. 4. A knurl support 14 in the general form of a lever or bell crank having a forwardly extending socket portion 15 and a depending portion 16 is pivotally mounted on a pin or shaft 17 between the brackets 13 for rocking or pivotal movement. A knurling member in the form of a roller 18 is journaled for rolling movement in the depending portion 16 of the knurl support 14 and projects rearwardly therefrom to a slight extent, as indicated at 19 (Figs. 1 and 4). An elongated hand lever 20 having an operating knob 21 fits into the socket portion 15 of the knurl support 14 and is detachably secured therein by means of a screw 22 adapted to engage a flattened portion 23 on the lever 20.

The knurling roller 18 is rotatably mounted in the knurl support 14 by means of a pair of bearing sleeves 24 (Fig. 5) keyed to the roller 18, the bearing sleeves 24 and the knurling roller 18 being clamped together and secured to the end of an elongated drive shaft 25 by means of a stud 26 extending longitudinally through the sleeves and the roller and threaded into the end of the shaft 25. A nut 27 is secured at the outer end of the stud 26 for retaining the sleeves 24 and the roller 18 in clamped relation. The drive shaft 25 extends longitudinally of the base 11 and is journaled at its opposite end in a depending link 28 pivotally attached by means of a pin 29 to an overhanging bracket 31, similar to the brackets 13, at the opposite end of the base 11. The pin 29 is aligned coaxially with the pin 17, and the distance between the axis of the pin 29 and the axis of the shaft 25 is the same as the distance between the axis of the pin 17 and the axis of the shaft 25, whereby to permit swinging movement of the shaft 25 paralleling the pivotal movement of the knurl support 14. A hand crank 32 extends through an aperture adjacent the outermost end of the shaft 25 and is secured thereto by means of a set screw 33 for manually rotating the drive shaft 25 and the knurling roller 18.

Projecting angularly and upwardly from the base 11 rearwardly of the bracket 31 is an anvil-supporting bracket 34 having an elongated anvil-supporting arm 36 rigidly secured thereto, as by a pair of screws 37, and extending parallel to the base 11 and the drive shaft 25. The outermost end of the arm 36 is provided with a pair of spaced projections between which is mounted for free rolling movement an anvil member in the form of a hard smooth surfaced roller 38 having approximately the same diameter and width as the knurling roller 18.

To provide a steady rest to facilitate locating or positioning a piston on the device prior to knurling, an elongated arm 39 having an outwardly bent end portion 41 extends rearwardly from the base 11 at the knurling end thereof. A piston

support, indicated generally at 42, is adjustably mounted on the bent end 41 of the arm 39 and is provided with a cradle or curved plate 43 at its upper portion for engaging the outer periphery of a piston, as shown in broken lines at 44. The lower portion of the piston support 42 below the bent end 41 of the arm 39 is split, as shown at 45, and is provided with a screw 46 threaded through the split portions thereof for clamping the support 42 to the bent end portion 41. The opposite end of the arm 39 is provided with a flattened portion 47 and is received within a connecting member 48 mounted on a supporting bar 49 which projects endwise from the base 11. A clamping screw 51 extends through the connecting member 48 and engages the bar 49 for clamping the latter against the flattened surface 47 of the arm 39 whereby to secure the arm 39 at any desired angular position relative to the bar 49 and the base 11.

It will be seen that by rocking movement of the knurl support 14 about the pin 17, as effected by the hand lever 20, the knurling roller 18 may be moved away from and toward the anvil roller 38. During a knurling operation, the skirt portion of the piston 44 is clamped between the two rollers, the anvil roller 38 being disposed against the interior surface of the piston skirt and the knurling roller 18 bearing against the outer periphery of the piston skirt with the axes of the rollers being parallel to the axis of the piston. As the knurling roller 18 is swung rearwardly of the device toward the anvil roller 38 by downward pressure on the lever 20, the drive shaft 25 also swings rearwardly as the link 28 swings freely about the pin 29 through a path paralleling the movement of the depending portion 16 of the knurl support 14.

In knurling a piston with the device shown in the drawings, the steady rest comprising the piston support 42 is adjusted as required to accommodate the size of the piston 44 to be knurled and to regulate the elevation of the piston above the base 11 so that the axis of the piston is in substantially the same horizontal plane as the axis of the anvil roller 38. When the piston 44 is thus properly positioned with its skirt portion in contact at its interior surface with the anvil roller 38, the steady rest is clamped in position by means of the screws 46 and 51.

With the lever 20 in lifted or raised position so that the knurling roller 18 is swung clear of the anvil roller 38, the skirt portion of the piston 44 is inserted between the rollers 18 and 38 to the desired extent. The knurling roller 18 is then moved into contact with the outer periphery of the piston skirt by downward movement of the hand lever 20 with sufficient hand pressure to sink the ridges of the knurling roller 18 into the skirt of the piston. In this position the piston 44 is stabilized by the clamping action of the rollers 38 and 18 and the knurling operation may then be carried out by rotating the hand crank 32 while the desired knurling pressure is controlled by the extent to which the operator presses down on the lever 20. Rotation of the hand crank 32 results in relative rolling movement between the knurling roller 18 and the piston 44 circumferentially of the latter. Because the skirt portion of the piston is clamped between the rollers 18 and 38, rotation of the knurling roller 18 also causes simultaneous rotation of the piston about its axis whereby to form an arcuate knurled band on the outer periphery of the skirt.

Because of the pivotal suspension of the knurling roller 18 between the supporting brackets 13, the operator of the knurling device can regulate the pressure with which the knurling roller 18 is pressed against the piston skirt while at the same time permitting the knurl support 14 to rock about the shaft 17 and thereby swing the roller 18 forwardly of the device in order to accommodate variations in piston diameter as the latter rotates about its axis. If, during the course of a knurling operation, the anvil roller 38 encounters an internal protuberance or other surface irregularity on the interior of the piston skirt, it will be seen that because the anvil roller 38 is mounted in rigid relationship to the base 11, the piston 44 will be displaced in a horizontal plane forwardly of the device, i. e. toward the knurling roller 18. As the piston 44 thus shifts, slightly in a horizontal plane transversely to its longitudinal axis, the knurl support 14 pivots in a counterclockwise direction, as viewed in Fig. 4, whereby to increase the spacing between the rollers 18 and 38 and thereby accommodate the variation in piston wall thickness at the point of knurling.

The above-described form of my invention possesses an important advantage in that the device is characterized by marked operating sensitivity. The knurling roller 18 being carried by the short arm of a lever or bell crank comprising the knurl support 14 and the knurling load or pressure being applied manually at the outer end of the long arm 20 of the lever, it will be seen that slight variations in piston wall thickness or other interior surface irregularities will be greatly magnified or emphasized resulting in a correspondingly greater degree of movement at the outer end of the arm 20. This increased degree of movement is immediately apparent to the hand of the operator and he may adjust the degree of downward hand pressure applied on the arm 20 accordingly as the roller 18 rocks inwardly and outwardly of the device. Thus, my device permits the application of substantially constant knurling pressure, as determined by the hand of the operator on the lever 20 in response to the rocking movement of the support 14, even when the radial spacing between the rollers 18 and 38 varies as the anvil roller 38 encounters surface irregularities on the interior of the piston skirt.

As hereinbefore mentioned, the diameters and widths of the knurling roller 18 and the anvil roller 38 are preferably substantially the same. Such a relationship insures that the anvil roller will have an area of engagement with the interior of the piston skirt which lies substantially within the area of engagement of the knurling roller with the exterior of the skirt, thereby avoiding any possibility of undesired peripheral distortion of the piston skirt as a result of the pressure between the knurling and anvil rollers. Of course, the swaging action of the knurling roller results in an increase in the effective diameter of the piston skirt, as hereinbefore described.

Although the invention has been described in detail with reference to one specific structural embodiment, it will be understood that various modifications and equivalent structures may be resorted to without departing from the scope of the invention as defined in the appended claim.

I claim:

A device for knurling the thrust faces of the skirt portion of a piston, comprising an elongated base having an intermediate portion provided with parallel front and rear sides adapted to be

gripped between the clamping jaws of a vise; a bracket extending upwardly from one end of said base and having a bifurcated rearwardly extending portion at its upper end; a lever pivotally supported within said rearwardly extending portion and having a forwardly extending portion and a depending portion which is slotted, a knurling roller rotatably mounted in the slot in said depending portion, a forwardly extending handle mounted in said forwardly extending portion, a similarly shaped bracket extending upwardly and rearwardly from the other end of the base, a link shaped similarly to said depending portion and pivotally suspended from said last mentioned bracket, a shaft rotatably supported by said link and said depending portion and connected at one end to said knurling roller and having a handle at its other end, a third bracket extending rearwardly and upward from said other end of the base, an elongated 15

10 arm mounted at one end on said third bracket and extending parallel to said base so that its other end is located adjacent said knurling roller, and an anvil roller rotatably mounted in said other end of said arm in alignment with said knurling roller, said knurling roller being swingable rearwardly toward said anvil roller by pressure downwardly on said forwardly extending handle to clamp the skirt of the piston between said rollers.

CERNY W. F. JONES.
